[57] CLAIM

The ornamental design for a combined ceiling fan housing, support rod and light fixture unit, as shown and described.

DESCRIPTION

FIG. 1 is a bottom perspective view of the combined ceiling fan housing, support rod and light fixture unit showing my design;

FIG. 2 is a bottom plan view thereof;

FIG. 3 is a side elevational view thereof;

FIG. 4 is a side elevational view thereof;

FIG. 5 is a side elevational view thereof;

FIG. 6 is a side elevational view thereof; and,

FIG. 7 is a top plan view thereof.

Any broken line illustration of environmental structure in the drawings is not part of the design sought to be patented. The support rod has been shown broken away in FIGS. 3–6 for ease of illustration.
